UNITED STATES PATENT OFFICE.

STANLEY McCATCHIE, OF CAMBRIDGE, MASSACHUSETTS, ASSIGNOR TO BENJAMIN ELECTRIC MANUFACTURING COMPANY, OF CHICAGO, ILLINOIS, A CORPORATION OF ILLINOIS.

ATTACHMENT PLUG.

Application filed November 20, 1920. Serial No. 425,328.

To all whom it may concern:

Be it known that I, STANLEY McCATCHIE, a citizen of the United States, residing at Cambridge, in the county of Middlesex and 5 State of Massachusetts, have invented new and useful Improvements in Attachment Plugs, of which the following is a full, clear, concise, and exact description, reference being had to the accompanying drawings, forming a part of this specification.

My invention relates to electrical connector devices and more particularly to attachment plugs.

One of the objects of my invention is to 15 cheapen the construction and lessen the danger of breakage by doing away with molded insulating parts.

A further object of my invention is to 20 provide an attachment plug which will be durable and efficient in use, and simple and compact in construction.

Further objects will appear from the detailed description to follow and from the appended claims:

25 In the drawings, in which two embodiments of my invention are shown—

Fig. 1 is a view of the inner or entering end of a swivel attachment plug;

Fig. 2 is a part sectional, part elevational 30 view of the swivel plug shown in Fig. 1:

Fig. 3 is a section on the line 3—3 of Fig. 2;

Fig. 4 is a plan view of an insulating fibre washer used in the plug construction;

35 Fig. 5 is a view of the inner or entering end of another form of plug embodying my invention;

Fig. 6 is a part sectional, part elevational view of the swivel shell plug shown in Fig. 40 5; and

Fig. 7 is a plan view of a sliding contact member used in the construction of Figs. 5 and 6.

Referring to Figs. 1, 2, 3 and 4, the construction shown therein comprises in a general way a swivel threaded shell contact 10,

a conical sliding contact member 11, having its circular edge swivelly connected with the inner or entering end of the threaded shell

50 contact at 12, a binding screw 13 threaded into the swivel contact member 11, a combined center contact and binding screw 14, a pair of insulating washers 15 and 16, by

means of which the center contact screw 14 is mounted on the sliding contact 11 and insulated with respect thereto, and a sheet metal stamping 17 which serves two purposes, that of clamping the insulating washers 15 and 16 in engagement with the sliding contact 11 and of confining the strands of the wire which lead to the center contact screw. A sheet metal handle member 18 is provided for screwing the threaded shell contact 10 into the socket, an insulating fibre band 19 being provided between the threaded shell contact 10 and the handle member. The three parts that is, the threaded shell, the insulating fibre band 19 and the handle member 18, are secured together by a circular series of corresponding depressions 20 formed in all three of the connecting members. By the above construction, it will be noted that the use of molded insulation is entirely avoided, whereby a light, cheap, practically unbreakable construction is secured.

Attention is called to the peculiarity of the tubular conductor confining portion 21 of the member 17, in that it is itself of metal, and yet serves to prevent the conductor from coming in contact with the sliding contact 11, through which the conductor passes to the center contact.

As shown in Figs. 2 and 3, this tubular cord confining portion 21 is spaced from the edge of the opening 21^a in the sliding contact 11 through which opening 21^a the tubular portion 21 extends. The member 17 has an eyelet portion 22 which extends through aligned openings in the insulating washers 15 and 16, this eyelet portion 22 being riveted over to firmly clamp the washers in engagement with the inwardly extending flange portion 23 of the sliding contact.

As shown in Fig. 2 the center contact screw 14 is threaded into this eyelet portion 22. In order to confine the loose strands of the wires and to keep them under the head of the center contact screw 14, the stamping 17 may have a semi-circular upwardly extending flange 24. The sliding contact member 11 is provided with an opening 25 located adjacent the binding screw 13 through which the wire passes, which leads to the binding screw 13.

In wiring the device, one of the wires is

passed through the tubular conductor confining member 20, and clamped underneath the head of the screw 14, and the other conductor is passed through the opening 25 and 5 clamped under the head of the binding screw 13.

In screwing the plug into the socket, the threaded shell contact 10 swivels on the sliding contact member 11 so that the cords are 10 not twisted by screwing in the plug.

In order to prevent chafing of the cords by the handle member 18, this handle member is provided with an inwardly extending cord confining portion 26, which forms a 15 smooth extending surface for the conductors to bear against.

The construction shown in Figs. 5, 6 and 7, is quite similar to the construction just described, except that here the sliding contact 20 member 26 is substantially flat instead of being conical and that the sheet metal stamping 27 which confines the cord leading to the center contact is of somewhat different construction, and in that the sheet metal 25 handle member 28 is elongated and reduced to enable the plug to be screwed into a socket which is difficult of access to the ordinary plug.

The stamping 27 is provided with a pair 30 of eyelet portions 29 by means of which it is secured to the sliding contact member 26, suitable insulating washers 30 being provided through which the eyelet portions 29 extend, for insulating the stamping 27 from 35 the sliding contact 26. In order to keep the strands of the conductor which is connected to the binding screw 13 away from the center contact screw 14, the sliding contact 26 is provided with a semi-circular upwardly 40 extending flange 31.

The sheet metal handle 28 may be provided at its outer end with a fibre band 32, forming a thumbpiece, this fibre band being slipped on over a reduced portion 33 45 of the handle, and held in place by flanging

over the sheet metal handle as indicated at 34.

While I have shown but two embodiments of my invention it may be embodied in other forms covered and defined by the appended 50 claims.

It is obvious that the handle shown in Fig. 6 may be substituted in the construction shown in Fig. 2.

Having thus described my invention what 55 I claim as new and desire to secure by Letters Patent of the United States is:

1. A swivel shell attachment plug comprising a threaded shell contact, a sheet metal cap member extending across the inner end 60 of said threaded shell contact, and having a swivel connection therewith, a binding plate member mounted on said sheet metal cap and insulated therefrom, a binding screw threaded into said binding plate, said 65 cap member having an opening therethrough, and an eyelet member extending through said opening for the conductor leading to said binding screw, said eyelet and said binding plate member being formed as 70 parts of an integral sheet metal stamping.

2. A swivel shell attachment plug comprising a threaded shell contact, a sheet metal cap member extending across the inner end 75 of said threaded shell contact and having a swivel connection therewith, a binding plate member having an eyelet portion integral therewith riveted to said sheet metal cap but insulated therefrom, a binding screw threaded into said eyelet portion, said cap 80 member having an opening therethrough and said binding plate member having a second eyelet portion extending through said opening to provide a guide and passage for the conductor leading to said binding screw, said 85 eyelets being formed as parts of an integral sheet metal stamping.

In witness whereof, I have hereunto subscribed my name.

STANLEY McCLATCHIE.
